ICE OR HOT WATER BREAST BAG

Elizabeth A. Freund, New York, N. Y.

Substitute for abandoned application Serial No. 726,388, May 18, 1934. This application November 21, 1941, Serial No. 420,018

1 Claim. (Cl. 150—2.2)

This invention relates to a bag for holding ice or hot or cold water for treatment of those portions of the female body that contain the milk glands, the general object of the invention being to shape the bag somewhat like a brassière, with means for supporting the bag by a back strap and a neck strap, the subject matter here being in substitution for the subject matter of abandoned application Serial No. 726,388, filed May 18, 1934 and allowed on October 18, 1934.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a view showing the invention in use.

Figure 2 is a section on line 2—2 of Figure 1.

Figure 3 is a section on line 3—3 of Figure 1.

As shown in the drawing, the bag A is made somewhat in the shape of a brassière, with a convex outer face and a concave inner face, with openings 1 in the bag for the passage of the breasts. The water or ice is placed in the bag through the nipple 3 which is closed by a plug 4 threaded in the nipple. The ends of the bag are formed with the tapered hollow extensions 5 to the ends of which are connected the straps 6 which are adapted to pass around the body of the user and to be connected together by the usual buckle 7 and holes 8. Two straps 9 are also connected to the upper part of the bag at the circular portions thereof and these straps are adapted to extend around the neck of the user and to be connected together by the buckle 10, the tongue of which is adapted to engage any one of a number of holes 11 in one of the straps.

A pair of substantially cup-shaped bags 12 is used when it is desired to cover the entire parts of the breasts and each of these bags 12 is formed with a filling opening closed by a plug 13 and each bag 12 is detachably connected to the main bag by the snap fasteners 14, portions of which are carried by the tabs 15 on the small bag and

portions by the outer face of the large bag, the latter portions surrounding the openings 1. Thus the small bags can be used or not, as desired.

5 The hollow extensions 5, of course, form part of the bag and receive the ice or water placed in the main part of the bag and these parts should extend under the armpits so that the bag covers those portions of the body which contain the 10 lacteal or milk glands, so that these glands can be treated by hot or cold applications by the use of the bag, and by using the small bags 12, the entire breasts can be treated.

The purpose of this invention is to supply a practical, safe and easy form for cold or hot applications, not only to the breasts themselves, but to the lacteal or milk glands, most of which are located at the base of the breasts and at the sides of the body approximately below the armpits and on a level with the breasts.

20 It is thought from the foregoing description that the advantages and novel features of the invention will be readily apparent.

It is to be understood that changes may be 25 made in the construction and in the combination and arrangement of the several parts, provided that such changes fall within the scope of the appended claim.

What is claimed is:

30 Means for treating those portions of the female body containing the milk glands, comprising a rubber bag made in the shape of a brassière and having elongated tapered and hollow end portions extending under the armpits, straps 35 connected to the ends of the bag and extending around the back of the user, means for connecting the straps together, a pair of neck straps connected with the top part of the bag, means for connecting the neck straps together, said bag 40 having a filling opening, a closure for the same, the front part of the bag having openings therein for the passage of the breasts, a pair of small substantially cup-shaped hollow bags adapted to cover the breasts, means for detachably connecting the small bags to the main bag around the 45 openings in the main bag, each small bag having a filling opening and closure means for the same.

ELIZABETH A. FREUND.
